INVENTOR

James J. Sullivan
BY
Frank D. Bussin
ATTORNEY.

UNITED STATES PATENT OFFICE.

JAMES J. SULLIVAN, OF PHILADELPHIA, PENNSYLVANIA, ASSIGNOR TO WILLIAM BROWN COMPANY, OF PHILADELPHIA, PENNSYLVANIA, A CORPORATION OF PENNSYLVANIA.

HOSIERY.

Application filed October 30, 1922. Serial No. 597,818.

To all whom it may concern:

Be it known that I, JAMES J. SULLIVAN, a citizen of the United States, residing at Philadelphia, county of Philadelphia, and State of Pennsylvania, have invented a new and useful Improvement in Hosiery, of which the following is a full, clear, and exact description, reference being had to the accompanying drawings, which form a part 10 of this specification.

My invention relates to an improvement in hosiery and more especially to ladies' hosiery.

Hosiery, and especially ladies' hosiery, is 15 subjected to a considerable strain by the supporter or garter, which is usually engaged with the welt of the stocking so that it will be smooth. The strain on the stocking is increased when the leg of the wearer is bent, 20 as when sitting down.

As a result of concentration of the strain on the stocking at the point, or points, where it is engaged by the supporter or garter, it very frequently happens that a thread in 25 the stocking gives way and as a result a run occurs, which spoils the appearance and eventually the usefulness of the stocking.

Various methods have been tried, by hosiery manufacturers, to prevent the deleterious 30 effect of the supporter on the stocking, but such means as have been tried, while in some cases serving their primary purpose, have been found in general unsatisfactory and have not been acceptable to the consuming public.

Now it is the object of my invention to provide an improved form of hosiery which is so constructed as to resist the tendency of the supporter or garter to injure the stocking and which at the same time will be otherwise satisfactory.

Having now indicated in general the nature, purposes and advantages of my invention, I will proceed to a detailed description of a preferred embodiment thereof with reference to the accompanying drawings, in which—

Fig. 1, is a side elevation, partly diagrammatic, of a stocking embodying my invention.

Fig. 2 is a section on line 2—2 Fig. 1.
Fig. 3 is a section on line 3—3 Fig. 2.

Fig. 4 is an enlarged diagrammatic view, of a portion of the stocking shown in Fig. 1, showing a detail of my invention.

55

The stocking comprises the leg portion *a* and the foot portion *b*, of usual construction, while to the upper end of the leg portion is attached, by the usual method, the top or welt *c*.

60

The welt *c* is formed from a section of fabric folded upon itself and the free edges of which are secured together and to the upper end of the leg portion of the stocking as shown in Figure 3. At opposite sides of 65 the welt, a block or reinforced section *d* is provided for the reception of the grip of a supporter or garter.

In the construction of the welt, the fabric is knitted, in the usual manner, using the 70 thread or threads *e* until the point is reached where the block is desired to commence. At this point an additional thread *f*, of a finer count and quality than the original thread *e*, is thrown in and the knitting continued 75 until a block of the desired width is produced. The additional thread *f* is then thrown out and the knitting with only the original thread *e* proceeded with until it is desired to insert another block, which is produced in a similar manner to the first. Thus, the main portion of the welt is composed of 80 one thread, while that portion within the area of the blocks is composed of such one thread with an additional thread of finer 85 count and quality.

In the use of the stocking in accordance with my invention, the grips of the supporter or garter are engaged with the welt within the area of the blocks, which, because 90 of their structure, absorb and resist the concentrated strain at the point of grip of the supporter without the possibility of injury to the main portion of the welt or to the leg of the stocking.

95

Due to the difference in size of the additional threads which form the blocks from the ordinary threads which form the main portion of the welt, the blocks are possessed of an elasticity and wear-resisting power 100 sufficient to absorb the strain of the supporter and at the same time without causing the welt to be materially increased in weight or to bind the leg of the wearer.

The use of a finer count thread in the production of the block gives to the block portion of the welt a distinctive appearance, which renders the proper point of attachment of the supporter grip obvious.

Having now fully described my invention, what I claim and desire to protect by Letters Patent is:

1. A stocking having a foot and leg portion and a welt, the welt being formed of yarn and provided with a block of small area relative to the welt and so located as to receive a garter attachment, formed by plaiting an additional thread of yarn, of finer count, on the welt.
2. A stocking having a foot and leg portion and a welt, the welt being formed from threads of yarn of equal count and provided with a block of small area relative to the welt

and so located as to receive a garter attachment, formed by plaiting an additional thread of yarn of finer count and greater strength than said welt forming threads on the welt.

3. A stocking having a foot and leg portion and a welt, the welt being formed from threads of yarn of equal count and provided with rectangular blocks of smaller area than the welt and oppositely located on the welt for the reception of garter attachments, formed by plaiting an additional thread of yarn, of finer count and greater strength than said welt forming threads, on the face of the welt.

In testimony of which invention, I have hereunto set my hand, at Philadelphia, Pa., on this 25th day of October, 1922.

JAMES J. SULLIVAN.
